CLAIM

The ornamental design for a light as shown and described.

DESCRIPTION

FIG. 1 is a perspective view of a light showing the claimed design;

FIG. 2 is the second perspective view thereof;

FIG. 3 is the third perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an exploded view of the light in a detached state.

FIG. 11 is a sectional view taken from within the dash-dot-dash line 11 of FIG. 1; and,

FIG. 12 is a sectional view taken from within the dash-dot-dash line 12 of FIG. 3.

The broken lines depict portions of the light that form no part of the claimed design.

In the drawings, the evenly-spaced broken lines show portions of a light that form no part of the claim; the dash-dot-dash broken lines represent enlarged sectional designations that form no part of the claim.

1 Claim, 12 Drawing Sheets
